BAKER

Walter E. Moore, St. Louis, Mo., assignor to Knapp-
Monarch Company, St. Louis, Mo., a corporation of Delaware

Application June 28, 1954, Serial No. 31,189

Term of patent 14 years

(Cl. D81—10)

To all whom it may concern:

Be it known that I, Walter E. Moore, a citizen of the United States and a resident of St. Louis and State of Missouri, have invented a new, original, and ornamental Design for a Baker, of which the following is a specification, reference being had to the accompanying drawing forming a part thereof:

I claim:

The ornamental design for a baker, substantially as shown.
